BUILDING

Cornelis van der Lely, 7 Bruschenrain, Zug, Switzerland

Filed May 12, 1972, Ser. No. 252,954

Term of patent 14 years

Int. Cl. D25—03
U.S. Cl. D13—1 B

FIG. 1 is a perspective view of a building embodying my new design.

FIG. 2 is a front elevation view; and

FIG. 3 is a side elevation view.

The sides of the structure not shown in the above figures are plain.

I claim:

The ornamental design for a building, as shown.
